UNITED STATES PATENT OFFICE

EDGAR B. ISAACS, OF MOUNT VERNON, NEW YORK, ASSIGNOR TO M. LOWENSTEIN & SONS, INC., OF NEW YORK, N. Y., A CORPORATION OF NEW YORK

DESIGN FOR A TEXTILE FABRIC

Application filed June 11, 1930. Serial No. 36,020. Term of patent 3½ years.

To all whom it may concern:

Be it known that I, EDGAR B. ISAACS, a citizen of the United States, and a resident of Mount Vernon, in the county of Westchester and State of New York, have invented the new, original, and ornamental Design for Textile Fabric, of which the following is a specification.

Reference is had to the accompanying drawings, forming part thereof, wherein the

figure is a plan view of a piece of textile fabric showing one repeat of my new design the unit of the design shown being repeated throughout the extent of the fabric in the relation indicated by the dot-and-dash lines.

What I claim is—

The ornamental design for textile fabric substantially as shown and described.

EDGAR B. ISAACS.
